UNITED STATES PATENT OFFICE.

SIDNEY HOWE SHORT, OF DENVER, COLORADO, ASSIGNOR TO THE UNITED STATES ELECTRIC COMPANY, OF SAME PLACE.

ELECTRIC ALARM AND SIGNAL BELL.

SPECIFICATION forming part of Letters Patent No. 357,865, dated February 15, 1887.

Application filed October 12, 1886. Serial No. 216,056. (No model.)

To all whom it may concern:

Be it known that I, SIDNEY HOWE SHORT, of Denver, in the county of Arapahoe and State of Colorado, have invented a new and useful Improvement in Electric Alarm and Signal Bells; and I do hereby declare that the following is a full, clear, and exact description of the same.

My invention relates to electric locomotives or street-cars propelled by electricity and arranged to run on a closed circuit; and it consists of a signal or alarm bell placed in the main circuit and adapted to be run by the current without breaking the circuit.

In street-cars operated by electricity, where the motors are placed in series on a single conductor arranged to supply them with power and made to be operated on a constantly-closed circuit, it is convenient and necessary to have an electric alarm-bell or signal-bell to warn persons of the approach of the cars. It is necessary for the bell to be operated by the motor driven from either end of the car, or for the conductor to ring it from within any car on a train of cars. The bell must be arranged to ring on a closed circuit, and in no way break the circuit while in operation.

This bell, hereinafter described, is especially arranged for electric locomotives, where it must run in series on a closed circuit; but it can be used on any closed circuit.

Figure 1 represents in side elevation the bell apparatus in connection with the platform of an ordinary street-car, but does not show the propelling motor or its connections, as they are not necessary to the explanation of this invention. Fig. 2 is a similar view of a modification.

Fig. 1 shows a vibrating bell arranged to ring continuously on a closed circuit as long as the foot or hand is pressed on the knob S or the short circuit around the bell is in any way opened. In this figure is shown an electro-magnet, M, which is connected by wires, w w', of low resistance with the opposite poles of the current-gatherer C of the car or locomotive. The poles of the magnet are also in circuit with a shunt consisting of wires x x', which are closed through a rigid contact, c, and a spring-contact, c'. The electro-magnet

M is shown as conveniently fixed to a depending support beneath the car, but may be fixed in any other position, as circumstances may dictate. The rigid contact c and spring-contact c' are fixed beneath the platform, as shown in the drawings, and are so arranged that a bolt, S', having a suitable head and dropped into a hole in the platform, rests on the spring-contact, so that any pressure applied by the foot on the head of the bolt will press down the spring and open the circuit, which is normally closed. The arrangement shown is adapted to be operated by the foot; but obviously it may be arranged to operate by the hand as well. While the spring is in contact with the rigid piece c the circuit is closed, and the current is short-circuited around the magnet M. On a spring, o, is suspended the armature a of the magnet M. The end of the armature carries a hammer, h, arranged, when the armature is drawn down, to strike a bell, B. The armature carries a contact-piece, j, connected by means of the spring o and wire y with the wire w of the electro-magnet circuit. The other wire, w', of that circuit is connected to an adjustable contact, i, in range with the contact j. When the contact at c c' is broken, the current is shunted through the electro-magnet M and the armature is brought down, which delivers a blow of the hammer upon the bell. At the same time the contact j is brought down to the adjustable contact-point i, and the current is thereby shunted around the electro-magnet and the armature released. This is repeated so long as the contact at c c' is broken; but the circuit is constantly maintained and the bell rings constantly while the shunt-circuit through c c' is broken. As before said, it is immaterial whether this be done by a pin arranged for the foot or hand.

In Fig. 2 I have shown a single-stroke bell arranged to work in a different manner, but in the same closed circuit. The electro-magnet in closed circuit, and the shunt-circuit through x x', and spring-contact with depressing piece S' are the same; but there is only the hammer h attached to the same spring-mounted armature, a. While the circuit through c c' is closed no current passes through

the coils of M and the bell is at rest; but when the circuit is broken by depression of c' the current passes through the coils of M and the armature is drawn down, thus causing a stroke 5 of the hammer upon the bell, which is returned by the release of the spring c' . This is repeated by repeated depressions of the pin S, making and breaking the circuit. The wire a' may be looped into and carried to the other 10 end of the car or to any part of it, and a spring-contact, $c^2 c^3$, like $c c'$, can be placed in circuit in this short circuit below the other platform, all as shown in Fig. 2, or in the cars. When the end of the line is reached and the 15 other end of the car becomes the front end, the driver lifts the button S and places it in a similar hole in that end, thus enabling him to control the bell and preventing any person else from ringing it.

20 I claim—

1. In combination with the current-gatherer of an electric car or locomotive, an electro-magnet in a closed circuit connected with said gatherer, a hammer on the armature of said 25 magnet, a bell arranged to be struck by said hammer when the armature is attracted by the magnet, a shunt-circuit having contact-pieces normally closed, and provided with means whereby the branch circuit may be opened, 30 substantially as described.

2. In combination with the current gatherer

of an electric car or locomotive, an electro-magnet in a closed circuit connected with said gatherer, a hammer on the armature of said magnet carrying a contact-piece connected to 35 the magnet-circuit and adapted, when the armature is drawn to the magnet, to bear on a contact, i , connected to the other wire of the armature-circuit, a bell arranged to be struck by said hammer when the armature is attracted by the magnet, a shunt-circuit having contact-pieces normally closed, and provided with means whereby the branch circuit may be opened, substantially as described.

3. In combination with the current-gatherer 45 of an electric car, an electro-magnet in a closed circuit connected with said gatherer, a hammer on the armature of said magnet, and a bell arranged to be struck by said hammer when the armature is drawn to the magnet, a 50 shunt around said magnet looped to both ends of the car and having contact-pieces normally closed, and means whereby the attendant may open the circuit, all substantially as described.

In testimony whereof I have signed my name 55 to this specification in the presence of two subscribing witnesses.

SIDNEY HOWE SHORT.
